UNITED STATES PATENT OFFICE

2,554,688

COMBINATION BAG AND SUNSHADE

Hans Vollweiler, New York, N. Y., assignor of one-half to Sigmund Lichtstern, New York, N. Y.

Application July 13, 1948, Serial No. 38,430

1 Claim. (Cl. 135—5)

1 This invention relates to a new article of luggage, and has for its principal object the provision of a novel, light-weight shopping, beach or garment-carrying bag which is simple and inexpensive in construction and which will be convenient for use and be adapted for a large variety of purposes. To this end the improved bag or carrier is of flexible material, preferably of canvas or other similar fabric, so that when not in use it may be rolled or folded into small compass, and comprises a body portion preferably folded on itself intermediate its ends, and which can be used when it is unfolded as a mat to lie on, for instance on the beach, or as a sunshade, or as a table cloth for picnics, or the like.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred forms of the invention have been shown.

In said drawings:

Figure 1 is a top plan view of a preferred embodiment of my invention as it appears while it is being used as a sunshade;

Fig. 2 is a side elevation of the same;

Fig. 3 is a front elevation of the device as it appears while it is being used as a beach bag, a shopping bag, or the like;

Fig. 4 is a cross-sectional view on the line 4—4 of Fig. 3;

Fig. 5 is an enlarged fractional sectional view on the line 5—5 of Fig. 1; and

Fig. 6 is a detailed, enlarged, exploded elevational view of a rod used in connection with the device.

Similar reference characters refer to similar parts throughout the several views.

In the drawing the numeral 1 denotes a longitudinal sheet of canvas or of any other suitable light-weight flexible material, which is foldable upon itself along a horizontal folding line intermediate its shorter end portions, the latter being folded back upon themselves and have their outer edges secured to the sheet so as to form tubular channels 2, which are of large diameter and open at both ends. On the sheet 1 there are provided slide fastener stringers 3 cooperating with sliders 4 or any other suitable fastening means for detachably securing to one another the halves of

2 those edges of said sheet which are right-angularly disposed to the sheet end portions that form the channels 2. The longitudinal edge portions of the sheet 1 at the ends of said horizontal folding line preferably are curved inwardly so as to form substantially V-shaped recesses, as may be seen in Figs. 1 and 2, and the stringers 3 follow these recesses. The corner portions of the sheet 1 are provided with apertures which preferably are reinforced by means of grommets 9 or the like, and slots 11 are provided in the sheet adjacent the channels 2.

When the device is used as a bag, the fasteners 3—4 are closed (Figs. 3 and 4), and several rod sections 5 and 6 are contained within the channels 2, thus stiffening the latter and reinforcing them, so that the bag can be carried conveniently with one hand extending through the registering slots 11 and gripping those portions 15 of the channels 2 which are adjacent the slots 11. Said channel portions having the quality of a well-sized double handle as long as the rod sections 5 and 6 are contained within the channels 2. Although there are shown four rod sections in 20 each channel 2 in Fig. 3, it will be obvious that fewer rod sections, for instance only two rod sections can be inserted into each channel 2, and the remaining rod sections can be placed within the bag, preferably at its bottom. At least some 25 of the rod sections for instance the sections 5, preferably are shorter than the sheet 1 is wide, so that some of them can be carried within the bag. Thus, by placing more or fewer rod sections 30 into the channels 2, a person can easily adjust the thickness of the handle to fit the size of his or her hand.

If it is desired to use the device as a picnic table cloth, or as a mat to lie on, or the like, the sliders 4 are moved down to the center of the 35 sheet 1, so that the latter can be unfolded (Fig. 1).

The rod sections 5 and 6 can be joined lengthwise to one another and can be used as vertical supports of the unfolded sheet 1, so that the latter can be used as sun shade or as a small roof. In 40 order to facilitate this, I prefer to provide a sleeve member 7 on each rod section 6, and to reduce the extremity 8 of each rod section 5 to such a diameter that it fits tightly through a grommet 9. After the rod sections 5 have been joined to the 45 rod sections 6, the latter are inserted into the ground, for instance into the sand of the beach, and resilient caps 10 of rubber or the like are stuck upon the extremities 8 of the rod sections 5 above the sheet 1, so that the latter cannot be 50 blown off by the wind.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which as a matter of language might be said to fall therebetween.

Having thus fully described my said invention, what I claim as new and desire to secure by Letters Patent in the United States is:

A device of the character described comprising a longitudinal sheet foldable upon itself along a horizontal folding line intermediate its shorter end portions and having curved V-shaped recesses at both ends of said folding line, said shorter end portions being folded back upon themselves and have their outer edges secured to the sheet so as to form tubular channels which are open at both ends and which are of large diameter; slide 25 fasteners being provided on the longitudinal sides of said sheet following said V-shaped recesses and being adapted for connecting to one another the halves of each longitudinal edge of the sheet

after the latter has been folded upon itself; and four longitudinal rods each of which has a reduced upper extremity and consists of two longitudinal sections provided with means for joining the sections lengthwise to each other; said sheet having reinforced apertures in its corner portions and being provided with slots adjacent said back folded end portions; the reduced upper extremities of said rods being adapted to be extended through said apertures in said sheet; resilient caps being detachably secured to the reduced extremities of said rods above said sheet; said tubular channels being adapted to receive four longitudinal sections of said rod.

HANS VOLLWEILER.
